HAIR PULLING TWEEZERS

Frederick L. Jerry, Detroit, Mich.

Application October 22, 1956, Serial No. 617,326

1 Claim. (Cl. 128—354)

This invention relates to improvement in hair pulling tweezers, the prime object of the invention being to devise a pair of tweezers that would enable the user to remove hair that is hidden in bumps that present tweezers can not get at, or removing of slivers, glass or other particles that might get embedded in one's hand, arm, legs or other parts of the body.

For the attainment of these and other such objects as may appear or be pointed out I have shown an embodiment of my invention in the accompanying drawing, 25 wherein:

Fig. 1 is a plan view of tweezers showing my invention attachment in broken lines.

2

Fig. 2 is a side section cut-away view of my invention attached to said tweezers.

Fig. 3 is a side view showing my invention attached to said tweezers.

5 The tweezers in Figures 1, 2 and 3 consist of two pinchers A1 and B1. Pincher A1 is provided with a slot 2 thus enabling button 3 to pass backward and forward. Button 3 is attached to plunger 4 which is provided with a needle 5. The plunger and needle assembly fits in 10 cylinder 6 which is secured to the under side of pincher A1. When button 3 is pushed forward, the needle 5 protrudes past the lip of A1, as shown in Figure 3. This enables the user of the said tweezers to lift the embedded particle in a position so that it can be pulled out of the 15 way by pulling back on the button 3.

I claim:

In a device of the class described the combination of 20 a pair of tweezers having attached thereon a cylinder having a plunger, the said plunger being provided with a needle whereby when the plunger is pushed forward in said cylinder the said needle protrudes out past said cylinder.
